UNITED STATES PATENT OFFICE.

TOM BRABSON, OF BROOKLYN, NEW YORK, ASSIGNOR TO BRABSON LAMP AND MANUFACTURING COMPANY, A CORPORATION OF NEW YORK.

INCANDESCENT GAS-LAMP.

SPECIFICATION forming part of Letters Patent No. 714,443, dated November 25, 1902.

Application filed April 25, 1901. Serial No. 57,477. (No model.)

To all whom it may concern:

Be it known that I, TOM BRABSON, a citizen of the United States, residing in the borough of Brooklyn, county of Kings, city and State 5 of New York, have invented certain new and useful Improvements in Incandescent Gas-Lamps, of which the following is a specification, reference being had therein to the accompanying drawings, in which—

10 Figure 1 is a side elevation of the lamp, the globe being shown in section; Fig. 2, a vertical sectional view of one of the burners; Fig. 3, a plan view of the adjustable mantle-support; Fig. 4, a side elevation of the mantle-support; Fig. 5, a horizontal sectional view on the line V V of Fig. 1, the mantles being removed; Fig. 6, a transverse vertical sectional view taken on the line VI VI of Fig. 5; Fig. 7, a vertical sectional view of the base- 15 piece or burner-support, taken on the line VII VII of Fig. 5; Fig. 8, a bottom view of the burner-support; and Fig. 9, a side elevation of the burner-support, the draft-directing shield, being shown in section and of a 20 slightly-different form.

25 One of the objects of the invention is to produce a lamp of simple construction, wherein a plurality of burners are supported on a base-piece which is secured centrally to the lower 30 end of the vertical supply-pipe, the burners being distributed equal distances apart around the supply-pipe and the base-piece being perforated to permit air to flow readily to the burners, and to provide the base with 35 a depending perforated draft-direct shield, whereby cool air from below will be drawn up through the perforated base to cool the same and the burners.

40 Another object of the invention is to provide means for suspending the mantles from the central supply-pipe, whereby said mantles may be independently or simultaneously 45 adjusted to the burners, and to provide pivoted globe-supporting arms which may be 50 swung laterally to permit the globe to be passed up over them and to be then drawn back in position to support the globe.

55 A further object of the invention is to provide a simple and efficient air and gas mixer

Other important objects of the invention and novel combination of parts will be hereinafter described.

Referring to the various parts by numerals, 1 designates a vertical supply and supporting pipe, to the lower end of which is threaded a circular base-piece or burner-support 2, which is perforated and is provided on its upper surface with four upward-extending externally-threaded nipples 3, which are adapted to receive the burners. These nipples communicate with passages 4 in depending radial ribs which are integral with the base-piece, said passages extending inward and downward and opening at their inner ends into a central vertical passage 5. This passage 5 communicates at its upper end with the supply-pipe 1 and at its lower end with a downward-extending drainage-tube 6, whose lower end is closed by a screw-cap 7. Clamped between 60 the screw-cap 7 and the bottom of the burner-support 2 is an air-directing annular shield 8, which is hollow and is provided with a series of apertures through which air is drawn by the burners. These apertures are located a 65 considerable distance below the burner-support to prevent the hot air about the base of the burners from being drawn in through the air-directing shield and to permit the cool air from below the burner-support to pass up 70 to the burners. The burner-support 2 is perforated between the ribs in order that the air may pass upward around the burners. In this manner a full supply of cool air is furnished which passes through the burner-support 75 on all sides of the burners, so that the supply will be uniform.

The air-directing shield at its top is equal in diameter to the burner-support, but tapers toward its lower end, so that the air after 80 passing through the perforations will have a substantially straight path to the perforations in the burner-support. In Fig. 9 the upper part of the shield is formed cylindrical, and from the lower edge of this cylindrical 85 part a substantially horizontal wall extends inward a short distance. In this wall are formed apertures for the admission of the air. From the inner end of this horizontal wall the shield is tapered toward its lower 90

95 and burner.

100

end, additional apertures being formed in this tapered part. It is obvious, however, that this shield may be of any desired shape.

The object of inclining the passages 4 inward and downward and connecting the passage 5 with the tube 6 is that these passages will be readily drained of any water which may be condensed in them or in the supply-pipe. It will also be seen that any deposit 10 lodging in these passages may be readily taken therefrom through the tube 6.

Threaded on each of the nipples 3 is a burner-coupling 9, which is provided at its upper end with a diaphragm 10, having small 15 perforations therein to reduce the amount of gas flowing to the burner. Threaded on the upper end of this coupling is the burner 11, which consists of the tubular part 12, which is provided near its lower end with an annular 20 series of air-inlets 13 and at its upper end with the enlarged annular chamber 14, across the upper end of which is secured the concave disk 15, of wire-gauze. Formed integral with the tubular part 12, just above the upper ends 25 of the openings 13, is an outward and downward extending air-directing hood 16, which is open at its lower end, said lower end extending below the lower ends of the openings 13. The object of this hood is to direct the upward- 30 flowing currents of air in through the openings 13 and to prevent any transverse currents or drafts through the tube. Fitting over the enlarged portion 14, so as to be slidably removable therefrom, is a tubular cap 17, whose 35 lower end rests on an annular flange 17^a, formed on the enlargement 14. This cap extends above the upper end of the enlargement 14, and across the upper end of said cap is secured a convex disk 18, of wire-gauze, a mixing-chamber 40 being formed between the two disks of gauze, as is clearly shown in Fig. 2. In the center of the upper gauze disk 18 is secured a circular spreader-plate 19, the object of which is to spread the upward-flowing gas 45 and air mixture and cause it to produce a tubular flame. It is obvious that the two disks of gauze may be secured in the chamber 14, if it is desired, and the cap 17 dispensed with.

To the central supply-pipe is adjustably 50 secured a spider 20, whose lateral arms 21 are vertically slotted to receive the vertical mantle-supporting rods 22, which are directly over the centers of the burners, the lower ends of 55 these rods being formed into hooks which engage the cross-wires secured in the tops of the mantles. These rods 22 are secured in the slots of the spider-arms 21 by means of screws 23, so that said rods are vertically 60 adjustable to permit the mantles to be independently adjusted to the burners, and the spider is vertically and rotatably adjustable on the supply-pipe by screw 30 in order that the mantles may be simultaneously adjusted 65 either up or down or around the supporting-pipe to properly locate the mantles over the

burners. It will of course be readily understood that the spider may be dispensed with and any other suitable horizontal support secured centrally on the supply-pipe in its place 70 and that said support may be provided with vertical perforations instead of slots to receive the mantle-supporting rods. It will also be readily understood that these arms may be secured in place by any suitable 75 means. Another object of hanging the mantles on the depending vertical rods 22 and securing said rods to the arms of the spider directly over the centers of the burners is to secure a rigid support for each of the mantles, which will not bend with the weight of the mantle when said support is heated, and to dispense with the usual mantle-supporting rod, which is secured to the burner and extends up outside of the mantle, its upper end 80 being bent laterally to engage the cross-wire in the top of the mantle, as these rods obstruct the lights and are unsightly.

On the base 2 are pivoted at their inner ends a series of horizontal globe-supporting 85 arms 24, which are adapted to permit the globe to be passed up above them and to be then swung outward to their radial positions to support the globe. The object of thus pivoting the globe-supporting arms so that 90 they will have a horizontal pivotal motion is that in putting the globe in place it will not be necessary to raise the globe as high as when the globe-supporting arms are swung up vertically. Another object of thus pivoting the 95 globe-supporting arms is that they may be readily reached and swung back into position to support the globe after the globe has been raised above the base.

The supply-pipe just above the base is provided with a valve 25, whose stem is extended beyond the vertical plane of the base and is provided with an operating-arm 26, to the outer end of which is connected a depending-operating-handle 27. Above this valve and 100 about on a level with the top of the mantles the supply-pipe is provided with a by-pass or pilot-light 28, a valve 29 being provided to regulate the flow of gas through said by-pass. The object of this pilot-light is to maintain a 105 small flame always burning at the top of the mantles to permit of the lighting of the lamp at any time by simply opening the valve 25.

Having thus described my invention, what I claim, and desire to secure by Letters Patent, is—

1. The combination of a supply-pipe, a perforated burner-support connected thereto, a series of burners mounted on said support and in communication with the supply-pipe, 115 and a downward-extending shield secured to and encircling the burner-support beyond the perforations therein whereby said perforations open within the shield and said shield prevents hot air about the burner-support 120 from being drawn in through the perforations in said support and permits cool air from be-

- low said support to pass through the perforations in the support to cool it and the burners and to give a full supply of air around each of the burners.
5. 2. The combination of a supply-pipe, a base secured thereto and formed with a central passage connected at its upper end with the supply-pipe, lateral ribs formed on the base and having downward and inward extending passages communicating at their lower inner ends with the central passage, the base being provided with perforations between the ribs, an air-shield secured to the base, a cap, closing the outlet from the central passage of the base and clamping the air-shield in place, and a series of burners on the base and in communication with the inclined passages of the base, substantially as described and for the purpose set forth.
10. 3. In a lamp, the combination of a burner-support, a series of upward-extending burners on said support, and a series of horizontal globe-supporting arms pivoted at their inner ends between the burners and adapted to swing inward to permit the globe to be passed over them, the burners forming stops to limit the movement of the arms and to prevent their outer ends moving in beyond the edge of the burner-support whereby said arms may 25 be readily engaged and swung outward to support the globe.
4. In an incandescent gas-lamp the combination of a vertical central supply-pipe, a series of upward-extending burners supported by said pipe and in communication therewith, a valve in the supply-pipe to control the flow to the burners, a by-pass in the pipe above the valve and adjacent the top of the mantles, and a valve to control the flow from 30 the by-pass whereby a permanent pilot-light may be maintained at the top of the mantles.
5. In an incandescent gas-lamp, the combination of a supply-pipe, a perforated burner-support connected thereto, a series of burners mounted on said support and in communication with the supply-pipe, each of said burners consisting of a tubular part formed with a series of air-inlets near its lower end, and an outward and downward 35 extending hood protecting said openings, an enlarged chamber in the top of the tubular part, two separated gauze disks in said chamber, a mixing-space being formed between said disks, and a downward-extending air-shield secured to the burner-support beyond the perforations therein whereby the said 40 perforations open within the shield and said shield prevents hot air about the burner-support from being drawn in through the perforations in said support and permits cool air from below said support to pass up through the perforations in the support to cool it and 45 the burners and to give a full supply of cool air around each of the burners.
50. 6. In a gas-lamp, the combination of a central vertical supply-pipe, a burner-support connected to the lower end thereof, and a series of burners mounted on said burner-support and in communication with the supply-pipe, each of said burners having an outlet for drainage at their lower ends.
55. 7. In an incandescent gas-lamp, the combination of a vertical central supply-pipe, a burner-support connected to the lower end thereof, a series of 55 burners mounted on the burner-support and in communication with the supply-pipe, each of said burners having an outlet for drainage at their lower ends.
8. In an incandescent gas-lamp, the combination of a supply-pipe, a perforated burner-support connected to the supply-pipe, a series 60 of burners mounted on said support and in communication with the supply-pipe each of said burners consisting of a tubular part formed with an air-inlet near its lower end, an enlarged chamber at the top of the tubular part, a gauze disk at the top of said chamber, and a downward-extending shield secured to the burner-support beyond the perforations therein whereby the said perforations open within the shield and said 65 shield prevents hot air about the burner-support from being drawn in through the perforations in said support and permits cool air from below said support to pass up through the perforations in the support to cool it and 70 the burners and to give a full supply of cool air around each of the burners.
9. In a gas-lamp, the combination of a central vertical supply-pipe, a burner-support connected to the lower end thereof, a series of 75 burners mounted on said burner-support, and a series of downwardly-extending passages from said burners and having an outlet for drainage at their lower ends.

TOM BRABSON.
